(57) **CLAIM**

(21) Appl. No.: **29/281,416**

The ornamental design for an operating console for an automobile, as shown and described.

(22) Filed: **Jun. 22, 2007**

DESCRIPTION

(30) **Foreign Application Priority Data**

Dec. 27, 2006 (DE) 4 06 06 494

FIG. 1 is a top perspective view of an operating console for an automobile, showing my new design;

(51) **LOC (9) Cl.** **12-16**

FIG. 2 is a top plan view thereof;

(52) **U.S. Cl.** **D12/415**

FIG. 3 is a rear perspective view thereof;

(58) **Field of Classification Search** D12/192,

FIG. 4 is a left side view, the right side being a mirror image thereof;

D12/415, 418, 400, 195, 190, 416-419, 421-426.1;

FIG. 5 is a bottom perspective view thereof;

D10/102, 98, 122-127, 46; D15/17, 28;

FIG. 6 is a perspective bottom view thereof; and,

D14/113, 124, 126, 129, 132, 133, 100; 296/190.02,

FIG. 7 is a top perspective view thereof.

296/190.03, 190.04, 190.05, 190.06, 190.07,

In the drawings, the broken line showing of center console controls depicts environmental subject matter and forms no part of the claim.

296/190.08, 190.09, 190, 191, 70, 929, 534;

224/311, 539; 248/309.1; 180/90; 280/750-752;

D23/327; 454/155; 16/110.1; D21/333;

15/28
